United States Patent Office

Des. 208,101

Patented July 18, 1967

208,101

LAMP

Walter Koziol, Russell, Ill., assignor to Charmglow Manufacturing Co., Antioch, Ill., a corporation of Illinois

Filed Nov. 14, 1966, Ser. No. 4,644

Term of patent 14 years

(Cl. D48—31)

Those elements shown in broken lines are for illustration only.

What is claimed is:

The ornamental design for a lamp, substantially as shown and described.
